UNITED STATES PATENT OFFICE.

BEN KING FORD, OF OAK PARK, ILLINOIS, ASSIGNOR TO WESTERN ELECTRIC COMPANY, INCORPORATED, OF NEW YORK, N. Y., A CORPORATION OF NEW YORK.

APPARATUS FOR AND METHOD OF WHIPPING CORES WITH STRAND MATERIAL.

Application filed September 2, 1924. Serial No. 735,230.

To all whom it may concern:

Be it known that I, BEN KING FORD, a citizen of the United States, residing at Oak Park, in the county of Cook and State of Illinois, have invented certain new and useful Improvements in an Apparatus for and Methods of Whipping Cores with Strand Material, of which the following is a full, clear, concise, and exact description.

10 This invention relates to an apparatus for and a method of whipping cores with strand material, and more particularly to an apparatus for and a method of whipping the ends of telephone cords preparatory to securing terminals thereto.

15 The object of the invention is to provide an improved apparatus for and a method of whipping cores with strand material.

In accordance with the general features 20 of the invention there is provided a whipping finger which draws a wire guided from a supply source and whips it about the end of a cord carried upon a support which is automatically moved back the desired distance for each turn of the wire whipped on the cord. The whipping finger is equipped with a retractable pin whereby a loop may be formed in the end of the wire. A mechanism controlled through a leverage system 25 is provided for retracting the pin as soon as the whipping operation commences. A modified mechanism is also provided, for retracting the pin, which is controlled through the centrifugal force created by the 30 revolving whipping finger.

The drawings illustrate the improved method for whipping the core and disclose an apparatus capable of performing the improved method, the major portion of which 40 is more fully disclosed in co-pending application, Serial No. 643,866, filed June 7, 1923 by H. H. C. Grondahl, which issued June 17, 1924 as No. 1,497,679.

It will be noted that in the structure disclosed in the above mentioned application the pin around which the end of the strand is looped is located on the cord support and that it is not retractable, whereas the pin, around which the end of the strand is looped, 50 disclosed herein is retractable and is located on the whipping means and not on the cord support.

Other objects and advantages of the invention will more fully appear as the follow-

ing detailed description progresses, wherein 55 reference is made to the accompanying drawings which illustrate one embodiment of the invention, and in which

Fig. 1 is a fragmentary side elevation of the complete mechanism with a section of 60 the cover removed;

Fig. 2 is an enlarged view of the whipping finger as shown in Fig. 1;

Fig. 3 is a plan view of the finger shown 65 in Fig. 2;

Fig. 4 is a section taken on the line 4—4 of Fig. 2 looking in the direction indicated by the arrows;

Fig. 5 is a view of the whipping finger 70 provided with a modified mechanism for retracting the pin around which the wire is looped;

Fig. 6 is a view of the cord after it has been removed from the whipping finger, and

Fig. 7 is a diagrammatic view showing 75 the way the wire is laid on the end of the cord.

It is believed that the method of whipping a strand on the cords will be readily understood from the following detailed description 80 of an apparatus by which it may be performed.

Referring now to the drawings in detail in which like reference numerals designate similar parts throughout the several views, 85 114 denotes a wire which is threaded from a supply spool 115, around a block 200, through a passage 131, around a guide roller 128, and through a passage 132 of a whipping finger 126. The block 200 may be attached to the finger 126 in any suitable manner. A conductor or cord support 87 is provided with a V-shaped depression 135 in its top surface within which the end of the cord to be whipped is placed with its end projecting 90 a suitable distance into a U-shaped formation of the whipping finger 126.

Passing through a hole 201 (Fig. 4) in the block 200 which is integral with the whipping finger 126, is a pin 202, one end 100 of which is adapted to normally project into the U-shaped formation of the whipping finger. Secured to one end of the pin 202 is a circular member 203 which is retained in the hole 201 by a pin 204 secured to the 105 walls of the hole 201. Surrounding the pin 202 and interposed between the member 203 and a portion of the finger denoted by refer-

ence character 205 is a normally compressed spring 206 (Fig. 4). The surface of the outer end of the member 203 engages the top surface of a block 207, secured to a link 208, which passes through a bearing 209 suitably secured to a bench 10. The lower end of the link 208 engages one end 210 of a bell crank lever 211 pivoted at a point 212 to a bracket 213 secured to the bench 10. A roller 215 is secured to another end 214 of the lever 211.

Pivotedly secured to a bracket 25, attached to the underside of the bench 10, is a lever 28, one end of which is connected to a suitable foot treadle or foot operating means (not shown) by a link 29. It will be noted that the lever 28 has been made longer than the one disclosed in the above noted application in order to provide an arm 217 which 20 is adapted to actuate the lever 211. A spring 30, one end of which is secured to the bench and the other end of which is secured to the lever 28, functions to return the lever 28 to its normal position after each 25 operation thereof. The other end of the lever 28 has a beveled surface 216 which is adapted to engage the roller 215.

The apparatus for causing the whipping finger 126 to rotate and for moving the support 87 rearwardly is fully disclosed in the aforementioned co-pending application.

The wire 114 after it has been withdrawn from the passage 132 is positioned, by forming or looping it around the end portion of the pin 202 which projects upwardly into the U-shaped formation of the finger 126, and is then drawn over a knife edge 229. The cord is then placed in the depression 135 of the support 87 with its end projecting a suitable distance into the U-shaped formation of the whipping finger 126 over the looped end of the wire. While holding the cord in the position above described the operator steps upon the foot pedal (not shown) causing the link 29 to draw one end of the lever 28 downwardly, causing the wire to be spirally whipped about both the core and the loop. By drawing one end of the lever 28 downwardly, the other travels upwardly, causing its beveled portion 216 to engage the roller 215, pivoting the lever 211, and drawing the link 208 downwardly. The link 208 in being drawn downwardly permits the spring 206 to expand, forcing the member 203 and the pin 202 downwardly into their lowermost position, the end of the pin 202 being caused to be retracted completely out of the U-shaped formation of the finger.

After the whipping operation is completed the cord is removed from the support and the wire 114 is severed therefrom; the whipped cord being shown in Fig. 6. The manner in which the wire is whipped about the core and the loop is readily apparent

from the diagrammatic view shown in Fig. 7. The pin 202 is then returned to its normal position ready for another cord.

The structure shown in Fig. 5 discloses a modified form of a whipping finger for accomplishing the same result as above described. It consists essentially of a pin 220, a portion of one end of which projects into the U-shaped formation of the whipping finger 126, the other end of the pin being pivotally secured at a point 228 to a lever 221 intermediate the ends of the said lever. One end 222 of the lever 221 is pivoted to a portion 230 of the finger 126, and the other end of the lever is formed into a weight 223. A spring 224 is secured at one end to a point 225 on the finger 126 and at its other end to a point 227 on the lever 221.

The wire is looped around the end of the pin 220 in a similar manner to that described in connection with the above mentioned pin 202. The cord is then laid in the support and the whipping mechanism is set in motion by the foot treadle. It is readily apparent that as soon as the finger 126 begins to revolve, the weight through centrifugal force, will cause the lever 221 to pivot outwardly expanding the spring 224 and causing pin 220 to be retracted out of the U-shaped formation of the whipping finger.

Upon the completion of the whipping operation the finger 126 is automatically stopped in its original position, as is more fully described in the above noted application, and the spring contracts, drawing the pin 220 back to its normal position. The cord is then removed from the support and the wire is severed therefrom.

The pin around which the strand is looped is retracted so that any undue twisting of the strand is prevented and the strand is whipped spirally around the loop and the end of the cord.

What is claimed is:

1. In a mechanism for whipping a core with a strand, means for whipping the strand around the core, and means carried by said whipping means for cooperating with the strand to form a loop in the end of the strand in position to be lapped by the whipping portion of said strand.

2. In a mechanism for whipping a core with a strand, means including a finger for whipping the strand around the core, a support for the core, means carried by the finger for locating the end of the strand in position to be lapped by the whipping portion of said strand and means for causing a relative movement between the support and the finger to cause the strand to be wound about the core.

3. In a mechanism for whipping a core with a strand, rotatable means for whipping the strand around the core, means carried

by said rotatable means designed to cooperate with the strand in forming a loop in the end of the strand, and centrifugal means for causing the said second mentioned means to 5 become inoperative at the start of the whipping operation.

4. A method of whipping a core with a strand, which consists in forming the end of the strand, bringing the formed end of 10 the strand and the core into contact, and thereafter whipping the core in such a manner that the formed end is covered by the strand whipped around the core.

5. A method of whipping a core with a strand, which consists in forming a loop 15 in the end of the strand, bringing the loop and the core into contact, and thereafter whipping the core in such a manner that the loop is covered by the strand, the ends of 20 the strand projecting from opposite ends of the whipping about the core.

6. In a mechanism for whipping a core with a strand, means for whipping the strand about the core, means carried by said 25 whipping means for locating the strand end in position to be lapped by the whipping portion of said strand, and means for causing said strand to be whipped in spiral formation about the core.

30 7. In a mechanism for whipping a core with a strand, means for whipping the strand about the core, and means carried by said whipping means for locating the strand end in proper position to be lapped by the 35 whipping portion thereof.

8. In a mechanism for whipping a core with a strand, means for whipping a strand

around a core, a support for the core, means carried by said whipping means for locating the strand end in position to be lapped 40 by the whipping portion of said strand, and means for causing a relative movement between the support and the whipping means to cause the strand to be whipped about the core and strand end. 45

9. In a mechanism for whipping the end of a core with a strand, means for whipping the strand around the core, and a retractable means carried by said whipping means 50 designed to cooperate with the strand in forming a loop in the end thereof in position to be lapped by the whipping portion of said strand.

10. In a mechanism for whipping the end of a core with a strand, means for whipping the strand around the core, a pin carried 55 by said whipping means designed to cooperate with the end of the strand, and means for retracting said pin at the start of the whipping operation.

11. In a mechanism for whipping the end of a core with a strand, means including a revolvable finger for whipping the strand around the core, a forming element carried 60 by said finger, designed to cooperate with the strand end, and means for causing the forming element to be carried into an inoperative position upon the revolution of the finger. 65

In witness whereof, I hereunto subscribe 70 my name this 20th day of August A. D., 1924.

BEN KING FORD.
